LOCK AND CLOSING UNIT FOR UPWARD ACTING DOORS

Matthew P. Graham, Detroit, Mich., assignor to
Crawford Door Company, Detroit, Mich., a corporation of Michigan

Application June 12, 1939, Serial No. 278,666

4 Claims. (Cl. 70—121)

This invention relates to a door closing and locking unit especially adapted for upward acting doors of the swinging type.

More particularly this invention relates to devices for drawing swinging type upward acting doors into a fully closed position.

The invention will be specifically hereinafter described in connection with upward acting doors of the swinging type, but it should be understood that the lock and closing units of the invention are not limited for use with such type of doors.

The usual locking devices for upward acting doors are not capable of drawing the doors to a fully closed position and are only effective in locking a fully closed door. However, in upward acting doors of the swinging type, the door may frequently come to rest in a partially opened position and must be manually forced into a fully closed position before it can be locked.

According to the present invention, closing units actuated by the door locking mechanism will draw the door into a fully closed position simultaneously with a locking of the door. The closing units of this invention include one or more U-shaped or offset arm members pivoted at one end on the inner face of the door near an edge thereof. The free end of the arm or U-shaped member is adapted to be moved beyond the adjacent edge of the door and thrust against a door jamb, fixed sill bracket, or the like, thus drawing the door into a fully closed position. The arms are actuated by a link mechanism operated from the door handle. A locking of the door handle will render each arm inoperative from the outside of the door so that these closure devices also effectively lock the door in closed position.

The invention eliminates the necessity for manually forcing an overhead door of the swinging type into fully closed position before it can be locked since an operation of the locking device will draw the partially open door into fully closed position.

It is, then, an object of the invention to provide closing units for doors capable of drawing the doors into a fully closed position.

Another object of the invention is to provide combination locking and closing units for doors.

A further object of the invention is to provide a simple, inexpensive locking unit for swinging type upward acting doors which simultaneously draws the door into fully closed position.

A further object of the invention is to provide an offset arm engageable with a door jamb, sill,

bracket or the like and operated by a lock mechanism for closing and locking a door.

Other and further objects of the invention will become apparent to those skilled in the art from the following detailed description of the annexed sheets of drawings which disclose preferred embodiments of the invention.

On the drawings:

Figure 1 is a vertical cross-sectional view taken through a doorway and illustrating, in side elevation, a swinging type upward acting door in closed and partially opened position and equipped with a closing unit and lock according to this invention.

Figure 2 is a fragmentary elevational view of the door and doorway shown in Figure 1 viewed from the inside thereof.

Figure 3 is an enlarged broken cross-sectional view taken along the line III—III of Figure 2.

Figure 4 is a broken inside elevational view of the structure shown in Figure 3.

Figure 5 is a broken cross-sectional view, with parts in elevation, taken through an upward acting door of the swinging type and illustrating a modified form of locking and closing device according to this invention.

Figure 6 is a broken inside elevational view of the structure shown in Figure 5.

Figure 7 is a vertical cross-sectional view, with parts in elevation, taken along the line VII—VII of Figure 3.

Figure 8 is a broken, fragmentary elevational view of a door and doorway viewed from the inside thereof and illustrating another modification of the locking and closing device of this invention wherein an offset arm engages a sill bracket instead of a door jamb.

Figure 9 is a vertical cross-sectional view, with parts in elevation, taken along the line IX—IX of Figure 8 and also illustrating, in dotted lines, the open or unlocked position of the offset arm.

As shown on the drawings:

In Figures 1 and 2 the reference numeral 10 designates a door for closing a doorway 11 in a building such as a garage or the like. The doorway 11 is defined by side door jambs 12, a floor or sill 13 and a lintel 14.

A horizontal track 15 extends into the building from each side jamb 12 near the top of the doorway 11. A roller 16 is carried by the top of the door 10 on each side thereof and projects into the tracks 15 for movement in said tracks.

Weatherstrips 17 are secured to the inner faces of the door jambs 12 and extend into the door-

way 11 from the sill or floor 13 to above the middle of the doorway.

Weatherstrips 18 are mounted on the inner face of the door 10 along the sides thereof and extend beyond the edges of the door for abutting the door jambs 12. The weatherstrips 18 extend from the tops of the weatherstrips 17 to the top of the door.

Brackets 19 are mounted on the door jambs 12 at about the middle of the doorway and pivotally carry link arms 20. The link arms 20 are pivotally connected at their other ends to the bottom portion of the door 10 on the inner face thereof.

15 A cable 21 is mounted at one end thereof to the lintel 14 at the center of the doorway. The cable extends from the lintel down along the outer face of the door and through the bottom portion of the door around a pulley 22 rotatably mounted in the door. The cable then extends from the pulley 22 along the inner face of the door to a winding drum 23 rotatably mounted on brackets such as 24 carried by the door 10 at the top thereof.

25 The winding drum 23 may be actuated by a spring or by other means to wind the cable 21 therearound and thereby counterbalance the door for moving the pulley 22 thereon toward the lintel 14. The door thus swings from a closed vertical position shown in dotted lines in Figure 1 to an outward position shown in solid lines in Figure 1 and thence upwardly to a fully open horizontal position. During this swinging movement of the door the bottom portion thereof is 30 guided by the link arms 20 and the top portion of the door rolls inwardly on the tracks 15. The weatherstrips 18 mounted on the door move away from the door jambs 12 since the upper portion of the door only moves inwardly from the doorway. However, the lower portion of the door 40 swings outwardly from the doorway during the opening operation and the weatherstrips 17 are therefore carried on the inner faces of the door jambs 12 so as not to interfere with the opening of the door.

45 When the door is pulled downwardly from its open overhead position by a manual tugging on the pull strap 25, it may not swing to a fully closed position for bringing the door into tight engagement with the weatherstrips 17 and for bringing the weatherstrips 18 into tight engagement with the door jambs 12.

The closing and locking unit of this invention will eliminate this possibility and insure a complete closing of the door so that the weatherstrips are in effective contact with abutting members.

As best shown in Figures 2, 3 and 4, a metal plate 26 is secured on the inner face of the door near one edge thereof and below the middle of the door. A hole 27 is cut through the door 10 to register with an aperture in the plate 26 as best shown in Figure 3.

A handle 28 is mounted on the outer face of the door to cover the hole 27. A square rod 29 extends from the handle 28 through the hole 27 and projects beyond the plate 26 on the inner face of the door.

As best shown in Figures 3 and 7, a washer 70 30 is disposed around the projecting end of the rod 29 and is rotatably seated in the aperture of the plate 26. A lock bar 31 has a square hole intermediate the ends thereof receiving the square rod 29 therethrough. As shown in Figures 3 and 75 4, this lock bar 31 extends beyond both sides of

the plate 26 and has the free end 31a thereof of a sufficient length to project beyond the inner edge of the weatherstrip 17 so as to thrust against this strip.

Outturned flanges 31b are bent back from the free end of the bar 31a as shown in Figure 4 so as to guide the bar behind the weatherstrip 17.

A washer 32 is next disposed around the projecting end of the rod 29 so that the bar 31 is carried on the rod between two washers 30 and 10 32. The required number of spacer washers 33 are next disposed over the free end of the rod 29 for urging the washer 32 against the bar 31. The end of the rod 29 is internally threaded for receiving the threaded shank of a bolt 34 which 15 draws the washers 33 against the washers 32 and holds the above described assembly on the projecting end of the rod 29. At the same time the handle 28 is held in rotatable relation on the outer face of the door. 20

As best shown in Figure 7, a lock 35 is mounted in the handle 28. This lock is operated by a key 36 which throws tumblers 37 into and out of recesses 38 in the lock handle. Thus when the key 36 is actuated to throw the tumblers 37 into the 25 recesses 38, a rotation of the handle 28 will turn the rod 29 for operating the lock bar 31. However, when the tumblers 37 are retracted by the key 36, the handle 28 will rotate freely around the rod 29 without turning the rod. The lock bar 30 31 then cannot be operated from outside of the door.

As shown in Figures 3 and 4, a handle 40 projects inwardly from the door 10 and is pivotally mounted on the inner end of the lock bar 31. 35 This handle 40 also serves to pivotally connect the end of a link rod 41 to the lock bar 31. As shown in Figure 2, the link rod 41 extends horizontally across the inner face of the door 10 near the bottom thereof and may be guided in the 40 center of the door by an eye 42 threaded into the door.

As shown in Figures 2, 3 and 4, a bracket 43 is secured on the inner face of the door at about the same level as the plate 26 but near the opposite edge of the door. This bracket has an apertured inwardly extending top flange 43a. A pivot pin 44 extends through the aperture of the flange 43a and pivotally supports the inner end of a bent or U-shaped arm 45 mounted on top of the flange 43a. This arm 45 extends inwardly around the guide arm 20 so as not to interfere with the operation of this arm. The free end 45a of the U-shaped arm 45 is adapted to thrust against the weatherstrip 17 for drawing the door 50 10 against the portion of the weatherstrip extending into the doorway 11.

A connecting member 46 is pivoted by means of a pin 47 to the base or bend of the U-shaped member 45. As shown in Figures 2 and 4, this connecting member 46 has a dependent apertured flange 46a through which the end of the link rod 41 is inserted. The link rod 41, as shown in Figure 3, is offset as at 41a so that the end thereof is in alignment with the bend of the U-shaped 55 arm 45.

Nuts 48 are threaded on the end of the link rod 41 on each side of the flange 46a to clamp the connecting member 46 to the end of the link rod. 70

As shown in dotted lines in Figure 3, a shifting of the link rod 41 by rotation of the lock bar 31 will retract the U-shaped arm 45 so as to bring the free end 45a thereof inwardly of the guide arm or link 20 and away from the weatherstrip 75 75

17. This rotation of the lock bar 31 will also move the free end 31a thereof inwardly of the edge of the door 10 to clear the weatherstrip 17. The door 10 is then unlocked and is free to be 5 swung outwardly into an open position.

A rotation of the lock bar 31 either by operation of the handle 28 or the handle 40 to bring the lock bar into a substantially horizontal position as shown in Figure 4 will clamp the free end 10 31a thereof against the weatherstrip and will simultaneously swing the U-shaped arm 45 for thrusting the free end 45a thereof against the opposite weatherstrip 17. This will, of course, draw the door 10 into a fully closed position even 15 though the door might have been in a partially open position before either handle was actuated.

In the modification shown in Figures 5 and 6, parts identical with parts described in Figures 1 to 4 are designated by the same reference numerals. In Figures 5 and 6, however, the lock handle 28 is mounted in the center of the door 10 instead of near one edge thereof. The lock bar 31 is replaced with a turn bar 50 fixedly carried on the projecting end of the square rod 29 25 so as to be rotated when the rod is turned by either handle 28 or 40.

As shown in Figure 6, the lower right-hand corner of the plate 26 is curved as at 26a. A pin 51 projects inwardly from the bar 50 to ride 30 along the curved portion 26a of the plate 26. This pin 51 will prevent movement of the bar 50 beyond the horizontal position shown in Figure 6, and also beyond the vertical position shown in dotted lines in Figure 6.

35 One end of the bar 50 receives the inside handle 40 thereon as in the structure described in Figures 2 to 4. The link rod 41 is secured to the connecting member 46 which actuates the U-shaped arm 45. However, the other end of the arm 50, instead of being free as in Figures 2 to 4, carries a pivot pin 52 pivotally receiving the apertured end of a second link rod 53. This link rod 53 is offset identically with the link rod 41 and is secured at its offset end to a second connecting member 54 by means of nuts 55. This 45 second connecting member 54 operates a second U-shaped arm 55 pivotally mounted on a bracket construction in a manner identical with the mounting of the U-shaped arm 45. The free end 50 of the arm 55 is adapted to thrust against the weatherstrip 17 on the opposite side of the door.

In the double arm structure shown in Figures 5 and 6, the door 10 can actually be drawn into a fully closed position by operation of either handle 28 or 40 for even a greater distance from closed position. Thus the arms 45 and 55 can begin acting against the weatherstrips 17 even when the bottom of the door 10 clears the doorway 11 entirely. The forcing of the door into a tight, 60 fully closed position by the closing unit of this invention is simultaneous with a locking of the door since, when the key 36 is retracted from the handle 28, this handle 28 is free to spin about the rod 29 and a rotation of the handle will not 65 affect the bar which actuates the closing means. It should be noted from Figures 3 and 5 that the pivotal connection 47 with the U-shaped arms 44 and 45 is closer to the edges of the door 10 than the pivotal connection 44 carrying these 70 arms on the brackets 43. This arrangement renders it substantially impossible to force the door open from a locked position because a mere bending of the link rods 41 and 53 will not permit sufficient movement of the U-shaped arms to 75 clear the weatherstrips 17.

In the modification shown in Figures 8 and 9, parts substantially identical with parts shown in Figures 1 to 7 have been designated by the same reference numerals. In this modification, however, the U-shaped arm is mounted for vertical movement on the inner face of the door and the free end of the arm engages a sill bracket. This construction is well suited for very wide doors since the arm can be mounted for vertical movement at or near the center of the door instead of being mounted for horizontal movement near a side edge of the door, and can engage a sill or floor bracket, instead of the door jamb, thus eliminating use of long connecting links from the handle to the arm. 15

As shown in Figures 8 and 9, the sill or floor 13 of the doorway 11 has an angle iron bracket 60 mounted in the center thereof. The leg 60a of the angle iron 60 is bolted to the floor or sill 13 by means of bolts 61. The leg 60b extends vertically upward into the doorway 11 for abutting the inner face of the door 10 at the bottom of the door as shown in Figure 9.

The lock handle 28 is mounted on the door at a convenient level above the bottom thereof and 25 at about the longitudinal center of the door as in Figures 5 and 6. The turn bar 50 on the inner face of the door, actuated by the lock handle 28, has a free end 50a and is only pivotally connected to one link rod 41. The link rod 41, instead of 30 extending transversely across the door as in Figures 2 to 6, extends downwardly toward the bottom of the door to the connector 46.

The bracket 43 is mounted near the bottom of the door 10 on the inner face thereof. The 35 bracket 43 is turned 90° from the positions shown in Figures 2 to 6, so that the flange 43a thereof is in a vertical plane. The arm 45 is pivoted to this vertical flange 43a by means of the pin 44 and the arm is thus mounted for movement in a 40 vertical plane instead of in a horizontal plane as in Figures 2 to 6. The connector 46 is connected to the bend of the arm 45 by means of a pin 47.

Rotation of the handle 28, when the key 36 is 45 rotated to unlock the handle, will cause a rotation of the turn bar 50, thus shifting the link rod 41 in a vertical plane and moving the arm 45 so that the free end 45a thereof will either thrust against the inner face of the flange 60b 50 as shown in solid lines in Figures 8 and 9 or will be retracted beyond the bottom of the door as shown in dotted lines in Figure 9.

The link rod 41 can be connected to the turn bar 50 through an inside handle 40 as in Figures 55 2 to 6 and this rod may also be provided with an offset portion so that the lower portion of the rod will be spaced inwardly from the door as shown in Figure 9.

One corner of the mounting plate 26 for the 60 turn bar 50 can be rounded as at 26a and the turn bar can have a lug or pin 51 movable around this rounded end so that the turn bar can only operate throughout a 90° angle.

When the door 10, as shown in Figures 8 and 9, 65 is to be locked, the arm 45 is in a retracted position as shown in dotted lines, and movement of either handle 28 or 40 to rotate the turn bar 50 will cause a shifting of the link 41 to carry the free end 45a of the arm beyond the bottom 70 edge of the door for abutting the angle iron 60.

Since the angle iron overlaps the bottom edge of the door the arm 45, in its locked position, need not extend below the bottom of the door.

Therefore, in the modification disclosed in 75

Figures 8 and 9, the U-shaped arm is mounted for movement in a vertical plane adjacent the bottom edge of the door toward and away from a floor bracket carried by the floor or sill defining the bottom of the doorway. A movement of the U-shaped arm from its retracted position into its locked position will cause the door to be drawn up tightly against the angle iron or locking bracket. Since the angle iron 60 is aligned with the weatherstrips on the sides of the door and doorway this drawing up of the door against the angle iron will also fully close the door into tight engagement with the weatherstrips.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In an upward acting door construction of the swinging type including a doorway, a door for closing said doorway, a radius arm pivoted to the bottom portion of the door at each side edge portion thereof and extending along the inner face of the door when the door is in closed position, and brackets secured to the sides of the doorway pivotally carrying said arms whereby the bottom portion of the door swings from closed vertical position to an overhead horizontal open position supported and guided through said radius arms, the improvements which comprise a U-shaped arm having one leg thereof pivoted to the inner face of the door adjacent a side edge of the door and the other leg thereof adapted to thrust against the side of the doorway to draw the bottom portion of the door into fully closed and locked position, said U-shaped arm in its locking position extending behind and around the adjacent radius arm in the path of movement thereof to further prevent opening of the door, and means for swinging the U-shaped arm about its pivot to clear the doorway and radius arm for allowing opening of the door.

2. In an upward acting door construction of the swinging type including a doorway, a door for closing said doorway, a radius arm pivoted to the bottom portion of the door at each side edge portion thereof and extending along the inner face of the door when the door is in closed position, and brackets secured to the sides of the doorway pivotally carrying said arms whereby the bottom portion of the door swings from closed vertical position to an overhead horizontal open position supported and guided by said radius arms, the improvements which comprise a first latching member pivoted to the inner face of the door adjacent a side edge thereof and having a free end adapted to thrust against the doorway for drawing the bottom portion of the door into fully closed and locked position, said first latching member in its locking position extending behind and around the adjacent radius arm in the path of movement thereof to further prevent opening of the door, a second latching member carried on the inner face of the door at the opposite side edge thereof having a free end portion adapted to thrust against the doorway, and common means for moving the free ends of the latching members into and out of thrusting engagement

with the doorway while at the same time moving said first latching member into and out of the path of the adjacent radius arm.

3. In an upward acting door construction including a doorway having side door jambs, brackets secured to the door jambs, a door mounted for movement into and out of the doorway, and radius arms extending along the inner face of the door between the brackets and bottom of the door and pivotally connected thereto whereby the bottom portion of the door is swingable from closed vertical position to overhead horizontal open position supported and guided through said radius arms, the improvements which comprise a rod extending through the door in spaced relation from the side edges thereof, a turnbar fixedly mounted intermediate its ends on said rod along the inner face of the door, a handle projecting from the outer face of the door adapted to rotate said rod for actuating the turnbar, links pivotally connected to the end portions of the turnbar and extending along the inner face of the door to the side edges thereof, U-shaped arms pivotally connected to the inner face of the door adjacent the side edges thereof adapted in their locking positions to extend behind and around said radius arms in the paths of movement of said radius arms and having free ends adapted to thrust against said door jambs for drawing the bottom portion of the door into fully closed and locked position, and means pivotally connecting said links with said U-shaped arms whereby rotation of the turnbar will shift the links longitudinally for moving the U-shaped arms inwardly from the path of the radius arms and outwardly around the radius arms to thrust against the door jambs, thereby locking and unlocking the door.

4. In an upward acting door construction including a doorway having side door jambs, brackets secured to the door jambs, a door mounted for movement into and out of the doorway, and radius arms extending along the inner face of the door between the brackets and bottom of the door and pivotally connected thereto whereby the bottom portion of the door swings from closed vertical position to an overhead horizontal open position supported and guided through said radius arms, the improvement which comprises a lock bar rotatably mounted on the inner face of the door adjacent one edge thereof having a free end adapted to extend between the door and the adjacent radius arm for thrusting against the door jamb, a rod pivotally connected to the other end of the lock bar extending across the inner face of the door to the opposite edge thereof, a U-shaped arm pivotally connected to the inner face of the door adjacent said opposite edge adapted in its locking position to extend around and behind the adjacent radius arm in the path of movement thereof and having a free end adapted to be moved into thrusting relation with the adjacent door jamb, said rod being pivotally connected to said U-shaped arm, and means for rotating the lock bar to move the free ends of the lock bar and U-shaped arm into thrusting engagement with the door jambs, thereby locking the door while simultaneously drawing the door into fully closed position.

MATTHEW P. GRAHAM.
